UNITED STATES PATENT OFFICE.

GEORGE BAYER, OF NEW YORK, N. Y.

LOCK.

SPECIFICATION forming part of Letters Patent No. 242,864, dated June 14, 1881.

Application filed September 16, 1880. (Model.)

To all whom it may concern:

Be it known that I, GEORGE BAYER, a citizen of the United States, residing at New York, in the county and State of New York, 5 have invented new and useful Improvements in Locks, of which the following is a specification.

The object of this invention is to produce a lock having the least possible width, for use 10 upon the doors and drawers or other parts of furniture; and to this end it consists in a sliding tumbler constructed with parallel slots and with a key-opening and a bolt-opening, which are arranged in a substantially rectilinear plane entirely within the edges of the tumbler, in combination with fixed guide-pins 15 engaging the slots, a sliding bolt constructed with a nib or projection engaging the bolt, and a key-arbor projecting into and through 20 the key-opening, as hereinafter more fully set forth.

This invention is illustrated in the accompanying drawings, in which Figure 1 represents a longitudinal central section. Fig. 2 is 25 a face view taken beneath the top plate. Fig. 3 is a like view taken beneath the tumbler.

Similar letters indicate corresponding parts. The letter A designates the sliding tumbler; 30 d d', the slots; f, the key-opening, and l the bolt-opening thereof.

B designates the sliding bolt, and C the lock-case inclosing the tumbler and bolt.

The slots d d' are parallel to each other, and are arranged at or near the opposite ends of the tumbler, while the openings f l are located 35 intermediate of the slots, in a rectilinear plane therewith and with each other, the whole being entirely within or between the edges of the tumbler, as clearly shown. e e' designate the 40 guide-pins engaging the parallel slots d d', these pins projecting inward from the back of the lock-case C.

The bolt B moves at a right angle to the tumbler A on a stump, h, fitted into a slot, i, 45 therein, this stump being a fixture of the lock-case.

k designates the nib or projection of the bolt engaging the bolt-opening l. This opening l is shaped with a contraction between its ends, through which the nib k passes when 50 the bolt is shot or retracted.

g designates the key-arbor projecting into the key-opening f from the back of the lock-case. This arbor receives the barrel of a key, N, the bit of which is so shaped that when 55 the key is turned it actuates both the tumbler A and the bolt B to shoot or retract the latter, as the case may be, one part of the bit impinging against the edge of the opening f and the other part passing behind the tumbler to catch in the usual notch of the bolt. 60

It will be seen that by the arrangement of the slots d d' and the openings f l in a substantially rectilinear plane within the edges of the tumbler the width of the lock can be reduced to a minimum, leaving the tumbler at 65 the same time of sufficient strength to withstand any strain to which it may be subjected in use.

I am aware that it is not new to construct 70 the tumbler of a lock with parallel slots co-operating with guide-pins, nor to construct it with a key-opening within the edges thereof, and I do not claim such, broadly; but

What I claim as new, and desire to secure 75 by Letters Patent, is—

The improved drawer-lock herein shown and described, the same consisting of the tumbler provided with end slots, d d', the key-opening f, and the bolt-opening l, with the lock-case 80 having the guide-pins, key-arbor, and locking-bolt provided with the nib k, all constructed and arranged as and for the purpose set forth.

In testimony whereof I have hereunto set my hand and seal in the presence of two subscribing witnesses. 85

GEO. BAYER. [L. S.]
